UNITED STATES PATENT OFFICE.

FRED C. ZEISBERG, OF WILMINGTON, DELAWARE, ASSIGNOR TO E. I. DU PONT DE NEMOURS POWDER COMPANY, OF WILMINGTON, DELAWARE, A CORPORATION OF NEW JERSEY.

PROCESS OF CONCENTRATING NITRIC ACID.

1,197,167.

Specification of Letters Patent. Patented Sept. 5, 1916.

Application filed October 15, 1914. Serial No. 866,781.

To all whom it may concern:

Be it known that I, FRED C. ZEISBERG, of Wilmington, in the county of New Castle, and in the State of Delaware, have invented 5 a certain new and useful Improvement in Processes of Concentrating Nitric Acid, and do hereby declare that the following is a full, clear, and exact description thereof.

My invention relates particularly to the 10 concentration of nitric acid, and incidentally to a method for the separation of nitric and sulfuric acids.

Hitherto it has been found that when concentrating weak nitric acid by mixing it 15 with a dehydrating agent as, for example, sulfuric acid, and distilling the mixture, the first portions of the distillate contain strong nitric acid but the later portions contain a considerable amount of water so that if all 20 of the distillate is recovered together, and without separating the different portions, a rather weak distillate is obtained. It has therefore been customary to obtain the latter portions of the distillate separately from 25 the first portions, and after mixing the same with sulfuric acid, to redistil the nitric acid mixture to obtain a more concentrated nitric acid.

The object of my invention is to avoid the 30 necessity of separating the different portions of the distillate and to provide a continuous process in which a highly concentrated nitric acid may be obtained.

A further object of my invention is to 35 provide a process of the above character in which there is only a very small amount of decomposition of the nitric acid.

A further object is to bring about the concentration of nitric acid in the presence of a 40 dehydrating agent without the necessity of introducing any water other than that contained in the nitric acid and the dehydrating agent.

A still further object is to utilize the 45 vapors of the dehydrating agent to assist in the dehydration of the nitric acid.

While my invention is capable of embodiment in many different forms, for the purpose of illustration I shall describe only one 50 form, and while it is capable of being carried out in many different forms of apparatus, I have shown only one form thereof in

the accompanying drawings, in which the figure is a diagrammatic representation of an apparatus that may be used for carrying 55 out my invention.

In the drawings I have shown a still 1 which has a draw-off pipe 2 at its side for drawing off the sulfuric acid that accumulates in the still. At the top of the still 1 60 there is a column 3 filled with any suitable filling material 3a, such as pumice stone, the same being retained in place by being supported upon a perforated plate 4 located in the bottom of the column. At the top of 65 the column 3 there is an inlet pipe 5 for mixed nitric and sulfuric acids, said pipe 5 having a stop-cock 6 and being connected to a tank 7 which contains the supply of mixed 70 nitric and sulfuric acids. From the top of 70 the column 3 a pipe 8 conducts the vaporized nitric acid to a condenser 9 located in a container 10 for circulating a current of cold water around the coil. Said coil 9 has an outlet pipe 11 for discharging the con- 75 densed nitric acid into a receptacle 12. The container 10 is provided with a valved cold water supply pipe 13 and a discharge water pipe 14. From the coil 9 a pipe 15 leads to the bottom of a tower 16 which contains any 80 suitable filling material, and which is provided with a valved water supply pipe 17 for supplying a current of water within the tower 16, which absorbs the lower oxides of nitrogen that pass out of the coil 9. The 85 water, with its dissolved oxides of nitrogen, passes out of the tower 16 by means of a pipe 18 and is collected in a receptacle 19. Any gases which are not absorbed in the column 16 may escape out of a pipe 20 located at the top of the column 16. A water supply pipe 21 provides a supply of water for the pipes 13 and 17.

In carrying out my process, the still 1 is 95 filled with sulfuric acid of any convenient strength as, for example, 80%, and is heated until the acid is boiling vigorously. When this occurs, a mixture of sulfuric and nitric acids is allowed to flow downwardly from the tank 7, or said acids are separately introduced into the column 3 where the acid mixture meets the ascending vapors from the boiling sulfuric acid. The nitric and sulfuric acids need not, however, be necessarily 100

introduced at the same level in the column 3. As a result the vapors are condensed and the heat given up by the condensing vapors drives out the nitric acid, which ascends in 5 the column freed from any water vapor, and finally passes out of the column through the pipe 8 as strong nitric acid vapor. The vapors are then conducted to the coil 9 where the nitric acid vapor is condensed and from 10 which it is collected in the receptacle 12. The small amounts of lower oxids of nitrogen resulting from the unavoidable decomposition of some of the nitric acid in the distillation are absorbed by the current of 15 water in the tower 16. The weak acid solution flowing out of the tower 16 is collected in the receptacle 19. The dilute sulfuric acid which collects in the still 1 flows out from the same through the pipe 2 from 20 which it may be collected and concentrated in any suitable manner, but preferably while hot to avoid the loss of heat.

In this process practically all of the nitric acid is obtained in a highly concentrated 25 condition. In this process only a small percentage of lower oxids of nitrogen is produced, owing to the fact that the nitric acid, upon being vaporized, immediately ascends to a cooler portion of the apparatus, the 30 temperature of the column 3 being such that it may be as low as 85° C. at the top. The product obtained is therefore of great utility, considering its high strength. In previous processes of obtaining nitric acid by distilling the mixture of sulfuric and nitric acids, the amounts of lower oxids formed 35 were much greater, owing to the fact that the nitric acid vapors came into contact with superheated portions of the still and 40 were there decomposed. The process is easy to control as it is a continuous one, and as it is merely necessary, in carrying out the process; to adjust the rate of flow of the incoming mixed acids. Furthermore, no wa- 45 ter need be introduced in the process other than that contained in the nitric and sulfuric acids introduced into the column.

As one example of my process, I may operate the process with a mixture of one part 50 of 50% nitric acid and three parts of 90% sulfuric acid. Upon distilling this mixture in the apparatus above referred to, a distillate is obtained which has a total acidity of 100%. The residual sulfuric acid 55 coming from the still 1 contains 77.6% sulfuric acid and less than 1% of nitric acid. The temperature of the top of the column 3 may be about 86° C. and in the still about 200° C. It is to be understood, of course, 60 that the above proportions and temperatures may be largely varied without departing from the spirit of my invention.

It is possible, by changing the proportions 65 and strengths of the acids introduced, to obtain a residual acid of any desired strength.

While I have described my invention above in detail, I wish it to be understood that many changes may be made therein without departing from the spirit of my invention.

70

I claim:

1. The process which comprises passing nitric acid and a dehydrating agent into a chamber, and driving off the nitric acid from the same by bringing into contact therewith water vapors obtained from a boiling aqueous solution of said dehydrating agent.

75

2. The process which comprises passing sulfuric and nitric acids into a chamber, and driving off the nitric acid from the same by bringing into contact therewith vapors from a boiling solution of sulfuric acid, condensing the nitric acid vapors, and recovering the residual oxids of nitrogen by absorbing the same in water.

80

3. The process which comprises continuously passing sulfuric and nitric acids into a chamber, and driving off the nitric acid from the same by bringing into contact therewith vapors from a boiling solution of sulfuric acid, condensing the nitric acid vapors, and recovering the residual oxids of nitrogen by absorbing the same in water.

85

4. The process which comprises continuously passing sulfuric and nitric acids into a chamber, and driving off the nitric acid from the same by bringing into contact therewith vapors from a boiling solution of sulfuric acid, and continuously removing the diluted sulfuric acid, condensing the nitric acid vapors, and recovering the residual oxids of nitrogen by absorbing the same in water.

90

5. The process of concentrating nitric acid which comprises passing nitric acid and a dehydrating agent into a chamber and driving off the nitric acid from the same by subjecting the nitric acid therein to the action of water vapors obtained from weak nitric acid previously concentrated by the same process.

105

6. The process of concentrating nitric acid which comprises passing nitric acid and sulfuric acid into a chamber and driving off the nitric acid from the same by subjecting the nitric acid therein to the action of water vapors obtained from weak nitric acid previously concentrated by the same process.

115

7. The process which comprises passing sulfuric and nitric acids in the form of a liquid into a chamber, and driving off the nitric acid from the same by bringing into contact therewith vapors from a boiling solution of sulfuric acid.

120

8. The process which comprises continuously passing sulfuric and nitric acids in the form of a liquid into a chamber and driving off the nitric acid from the same by bringing into contact therewith vapors from a boiling solution of sulfuric acid.

125

130

9. The process which comprises continuously passing sulfuric and nitric acids in the form of a liquid into a chamber, and driving off the nitric acid from the same by
5 bringing into contact therewith vapors from a boiling solution of sulfuric acid, and continuously removing the diluted sulfuric acid.

In testimony that I claim the foregoing I have hereunto set my hand.

FRED C. ZEISBERG.
